Primary Examiner — Garth Rademaker*Assistant Examiner* — Laura H Yu(74) Attorney, Agent, or Firm — Wells St. John P.S.(57) CLAIM

The ornamental design for a writing utensil as shown and described.

DESCRIPTION

FIG. 1 is an isometric view of a writing utensil showing my new design with dashed lines representing an example writing utensil tip;

FIG. 2 is another isometric view thereof;

FIG. 3 is a side view thereof;

FIG. 4 is another side view thereof;

FIG. 5 is a bottom view thereof; and,

FIG. 6 is a top view thereof.

The broken lines in the figures illustrate a writing utensil tip and form no part of the claimed design.

1 Claim, 5 Drawing Sheets(56)
